UNITED STATES PATENT OFFICE.

HARRY A. TAYLOR, OF NEW YORK, N. Y.

DESIGN FOR A LADY'S UNDERVEST.

SPECIFICATION forming part of **Design No. 29,913**, dated December 27, 1898.

Application filed November 28, 1898. Serial No. 697,704. Term of patent 3½ years.

To all whom it may concern:

Be it known that I, HARRY A. TAYLOR, a citizen of the United States, residing at New York city, borough of Manhattan, State of New York, have invented and produced a new and useful Design for Ladies' Undervests, of which the following is a specification.

In the drawings, Figure 1 is a perspective view, and Fig. 2 a side elevation, of my new design.

My design consists of a tubular body portion *a*, of ribbed knitted fabric, the ribs running longitudinally from end to end and the upper and lower ends being substantially straight across. The opposite sides of this body portion, at its upper end, are cut away at *b*, and projecting from the edge of each of these notched portions is a tubular part *c*, also of ribbed-knitted fabric, the ribs running at substantially right angles to the ribs on the main body. The pieces *c* project above

the upper end of the body portion about half their length and they taper upward their full height, forming narrow strap portions *d* at the top.

It will be observed that the tubular wings *c* stand outward from the upper corners of the body at an angle of about forty-five degrees and that the parts of said wings that project above the body portion project outward therefrom.

I claim—

The design for a lady's undervest substantially as herein shown and described.

In testimony whereof I hereunto affix my signature, in the presence of two witnesses, this 16th day of November, 1898.

HARRY A. TAYLOR.

Witnesses:

J. M. SHELLABARGER,
CHARLES J. HARDY.
